COMBINED CUP AND COVER THEREFOR

Mary E. Fradette, 620 Arrow St., Parker, Fla.

Filed May 9, 1962, Ser. No. 70,057

Term of patent 14 years

(Cl. D44—9)

Fig. 1.

Fig. 2.

I claim:

The ornamental design for a combined cup and cover therefor, as shown.
